INK DRYING MEANS FOR STOCK QUOTATION PROJECTING MACHINES

August D. Eitzen, Rockville Centre, N. Y., assignor to News Projection Corporation, New York, N. Y., a corporation of New York

Application September 4, 1929, Serial No. 390,372
Renewed May 27, 1933

13 Claims. (Cl. 88—24)

My present invention relates generally to stock ticker apparatus and has particular reference to a stock ticker projection machine.

A particular object of my present invention lies in providing efficient and simple mechanism for drying the tape, i. e., drying the ink or pigment thereon, in a quick and reliable manner.

In communities where the rental or purchase value of tickers is relatively high, it is frequently desirable to allow the marked tape to accumulate in a basket or the like and not to be completely rewound, so that perusal of the tape after it has passed through a suitable projecting device and at a considerably later time may still be possible without inconvenience. Frequently, in moist climates, such subsequent examination of the tape is accompanied by considerable annoyance because of the fact that the ink or pigment has not completely dried. Similarly, regardless of climate, the employment of a tape which is not of paper but of a more transparent character such as cellophane, is similarly accompanied by a very slow drying of the markings on the tape.

One of the main features of my present invention lies in providing means for blowing air over the tape in a simple and expeditious manner for efficiently and rapidly drying the tape to render it subsequently examinable without undue inconvenience.

In a preferred embodiment, I provide, in combination with a stock ticker and a projecting device, a housing mounted beneath the ticker and projector and containing a tape-pulling mechanism; and I provide means mounted within this housing for blowing air or a similar drying medium over the tape after the latter has passed through the projecting device.

A further object lies in providing a mechanism which allows for selective adjustment for either re-winding the tape immediately after its passage through the projecting device, or for directing the tape in a loose condition into a suitable receptacle. Where the tape is immediately rewound, the previous drying thereof assures an unsmudged condition of the rewound tape so that the same may be re-projected or re-examined without annoyance.

Another object of my invention is to provide a construction wherein the means for drying the tape fulfills an additional function in connection with the cooling of the projecting device. A double advantage is achieved by me in drawing the heated air out of the projecting device and simultaneously employing this heated air for the purpose of drying the tape.

An important feature of my invention lies in providing a mechanism wherein a single driving apparatus serves simultaneously to operate not only the tape-pulling mechanism but also the blower or similar instrumentality for providing the requisite air.

In general, it is an object of my invention to provide an apparatus which is simple in construction, inexpensive to manufacture and install, and efficient and reliable in operation.

For the attainment of the foregoing objects and such other objects as may hereinafter appear or be pointed out, I have illustrated one form of my invention in the accompanying drawings, in which—

Figure 1 is an elevational view partly in section of an assembly embodying the features of my present invention; and

Figure 2 is a side view, also partly in section.

I have shown a stock ticker 10 adapted to discharge a marked tape 11, the latter passing through a projecting device 12 of substantially customary construction. For example, the projecting device 12 comprises the main housing 13 within which illuminating means are provided, 25 and the lateral housing 14 through which the tape passes, the housing 14 carrying above it a suitable objective lens or the like 15 for projecting the beam of light upwardly onto a screen.

In accordance with my present invention, I 30 mount the ticker 10 and the device 12 above a housing or chamber 16 within which the tape-pulling mechanism and other elements of my present construction are arranged. I have, for example, provided a tape-pulling mechanism 35 which consists of a spindle 17 constantly rotated by means of a worm wheel 18 axially mounted therewith, the wheel 18 deriving its motion from a worm 19 mounted upon a shaft 20, the latter being driven by means of a belt 21 or the like 40 from the shaft of an electric motor 22. The tape 11 is caused to pass beneath a guide roller 23, thence over and around the spindle 17, thence underneath the guide roller 24, from which latter point it may be directed either onto 45 a receiving and re-winding mandrel 25 or through a suitable outlet opening in the housing 16, as shown in full lines in Figure 1. The dot and dash line 26 of Figure 1 illustrates the manner in which the tape may, if desired, be directed 50 immediately onto the receiving mandrel 25.

The mandrel 25 is driven from the shaft of the spindle 17 by means of a belt or the like 27, and a guide roller 28 adjacent to the outlet opening previously mentioned is caused to rotate by 55

means of a belt or the like 29 extending from the shaft of the mandrel 25. A spring-pressed roller 30 bears against the tape as the latter passes over the spindle 17.

5 In accordance with my present invention, I provide a conduit 31 constituting a narrow elongated housing for completely enclosing the tape 11 during its passage from the projecting device 12 to the tape-pulling mechanism and thereby 10 positively protecting it from engagement by a trader. The upper end of this conduit is restricted and below such restriction is in communication by means of an opening 32 with the interior of the lateral projecting device housing 14, and the latter is in communication with the interior of the main housing 13 by means of the suitably prepared apertures or openings 33. The conduit 31 extends downwardly into the chamber 16 and terminates closely adjacent to the 20 first guide roller 23, at which point it is again restricted by a hinged or pivoted cover 34 which permits access for the purpose of threading or inspection.

25 Mounted upon the shaft of the motor 22 is a blower 35 whose inlet opening 36 is caused to communicate with the interior of the conduit 31. I have illustratively shown a pipe 37 opening into a chamber 38 adjacent to the conduit 31 and provided with apertures 39 communicating 30 with the interior of the conduit 31. It is to be noted that these apertures are so arranged as to apply the suction of the blower edgewise with respect to the tape.

35 When the apparatus functions, the motor serves not only to drive the tape-pulling mechanism, the re-winding mechanism and all the other portions belted or connected thereto, but also to operate the blower 35. This causes heated air to be drawn out of the housing 13 through 40 the openings 33 and then through the opening 32 into the upper end of the conduit 31, thence downwardly. At this stage, the heated air serves to dry the tape passing through the conduit. At the lower end of the conduit, the air passes outwardly through the apertures 39 into the chamber 38 and thence through the conduit 37. In this way, the projecting device is not only kept 45 in a cooled condition by the removal of the heated air, but the tape is at the same time efficiently dried by means of this same heated air.

50 It will be obvious that the employment of this apparatus is an extremely inexpensive matter. At the same time, it is to be noted that an efficient drying of the tape is accomplished, whereby 55 the latter may be subsequently examined and handled without inconvenience. For example, the tape 11 emanating from the left side of the apparatus in Figure 1 may be caused to collect in a basket or suitable receptacle, and whether 60 this tape be of paper or any other material, and whether the climate be moist or dry, free inspection may be had of the collected tape without any danger of smudging the latter or soiling the hands.

65 It will be obvious that changes in the details herein described and illustrated for the purpose of explaining the nature of my invention may be made by those skilled in the art without departing from the spirit and scope of the invention as expressed in the appended claims. It is therefore intended that these details be interpreted as illustrative, and not in a limiting sense.

Having thus described my invention and illustrated its use, what I claim as new and desire to 75 secure by Letters Patent is—

1. In a stock ticker projection machine, a ticker adapted to produce inked impressions on a tape prior to its discharge from said ticker, a projecting device, an inspection area, a tape-pulling mechanism for drawing the tape to said inspection area through said device as it is discharged by said ticker, and means for drying the inked impressions on the tape during its passage to the tape-pulling mechanism after the tape leaves said device and before it passes to said 10 tape pulling mechanism.

2. In a stock ticker projection machine, a ticker adapted to produce inked impressions on a tape prior to its discharge from said ticker, a projecting device, a tape-pulling mechanism for 15 drawing the tape through said device as it is discharged by said ticker, and means for blowing air over the tape after it leaves said device to dry the inked impressions on the latter during its passage to the tape-pulling mechanism. 20

3. In a stock ticker projection machine, a ticker adapted to produce inked impressions on a tape prior to its discharge from said ticker, a projecting device, a tape-pulling mechanism for drawing the tape through said device as it is discharged by said ticker, and means for blowing air over the tape to dry the inked impressions on the latter during its passage to the tape-pulling mechanism; said means comprising a conduit for the tape, and a blower whose inlet is connected 30 with the interior of said conduit.

4. In a stock ticker projection machine, a ticker adapted to produce inked impressions on a tape prior to its discharge from said ticker, a projecting device, a tape-pulling mechanism for 35 drawing the tape through said device as it is discharged by said ticker, and a blower for directing air over the tape after it leaves said device to dry the inked impressions on the latter after it leaves the projecting device and before the tape 40 passes to said tape pulling mechanism.

5. In a stock ticker projection machine, a ticker adapted to produce inked impressions on a tape prior to its discharge from said ticker, a projecting device, a tape-pulling mechanism for 45 drawing the tape through said device as it is discharged by said ticker, a conduit for the tape leaving the projecting device, and means for blowing air through said conduit so as to dry the inked impressions on the tape. 50

6. In a stock ticker projection machine, a ticker adapted to produce inked impressions on a tape prior to its discharge from said ticker, a projecting device, a tape-pulling mechanism for drawing the tape through said device as it is 55 discharged by said ticker, a conduit for the tape leaving the projecting device, means for establishing communication between said conduit and the interior of said projecting device, and means for drawing the heated air from the interior of 60 the projecting device into and through said conduit so as to dry the inked impressions on the tape and also cool the projecting device.

7. In a stock ticker projection machine, a ticker adapted to produce inked impressions on a tape 65 prior to its discharge from said ticker, a projecting device, a tape-pulling mechanism for drawing the tape through said device as it is discharged by said ticker, a conduit for the tape leaving the projecting device, and means for 70 simultaneously driving said tape-pulling mechanism and blowing air through said conduit to dry the inked impressions on the tape.

8. In a stock ticker projection machine, a ticker adapted to produce inked impressions on a 75

- tape prior to its discharge from said ticker, a projecting device, a tape-pulling mechanism for drawing the tape through said device as it is discharged by said ticker, a motor for driving said mechanism, and means operated by said motor for blowing air over the tape after it leaves said device and before the tape passes to said tape pulling mechanism to dry the inked impressions on the latter.
9. In a stock ticker projection machine, a ticker adapted to produce inked impressions on a tape prior to its discharge from said ticker, a projecting device, a housing beneath said ticker and projecting device, a tape-pulling mechanism in said housing for drawing the tape through said projecting device as it is discharged by said ticker, a conduit for the tape extending from the projecting device downwardly into said housing, and a blower mounted in said housing and having its inlet in communication with said conduit so as to draw air over the tape to dry the inked impressions on the latter on its passage to the pulling mechanism.
10. In a stock ticker projection machine, a ticker adapted to produce inked impressions on a tape prior to its discharge from said ticker, a projecting device, a housing beneath said ticker and projecting device, a tape-pulling mechanism in said housing for drawing the tape through said projecting device as it is discharged by said ticker, a conduit for the tape extending from the projecting device downwardly into said housing, the upper end of the conduit being in communication with the interior of the projecting device, and a blower mounted in said housing for drawing air from the interior of the projecting device into and through said conduit for drying the inked impressions on the tape.
11. The combination with a ticker adapted to produce inked impressions on a tape prior to its discharge from said ticker, of an inspection location where the tape may be handled by a trader, a heat retaining and tape protecting housing, heating means for supplying heat to the interior of said housing, to dry the inked impressions on the tape during its passage through said housing, said housing being elongated and narrow at its ends to form a narrow elongated tape passage to retain the heat as long as possible and confine it to the elongated narrow passage through which the tape passes, said housing being further composed of rigid material to clear the housing from engagement with the tape while passing therethrough and remove the tape from position to be handled by a trader, and a tape pulling device for drawing the tape through said housing to said inspection location.
12. The combination with a ticker adapted to produce inked impressions on a tape prior to its discharge from said ticker, of a guide for positioning a portion of the tape so marked by said ticker to facilitate handling the tape while inspecting the same, a heating device for drying the inked impressions on the tape before arriving at said guide, and a tape pulling device for drawing the tape through said heating device to said guide.
13. The combination with a ticker adapted to produce inked impressions on a tape prior to its discharge from said ticker, of guide rollers for guiding the tape so marked by said ticker into position to be inspected, a heating device for drying the inked impressions on the tape before arriving at said inspection location, and a tape pulling device associated with said guide rollers for drawing the tape through said heating device to said inspection location.

AUGUST D. EITZEN.
